UNITED STATES PATENT OFFICE

2,029,180

NECKTIE CONSTRUCTION

William Mayer, New York, N. Y.

Application July 27, 1935, Serial No. 33,483.

2 Claims. (Cl. 2—155)

My present invention relates generally to neckwear, and has reference to an improved type of adjustable neckband.

It is a general object of my invention to provide an improved adjustable necktie, of the general character illustrated in United States Letters Patent No. 2,003,359, issued June 4, 1935. This type of necktie has a neckband portion which is adjustable in length by doubling it back upon itself 10 and by providing at its end a hook which is adapted to engage with a selected one of a series of openings or perforations in the neckband.

The more specific objects of the present invention include the provision of an improved assembly of parts, whereby the tie is of enhanced attractive appearance, more compact in nature, easier to pass through or around a collar or neckband, and of a simple structural nature which permits the tie to be manufactured at very small 20 expense.

As in the construction described in the aforementioned patent, the present construction permits the production of a tie by the usual and customary steps, and involves the mere additional 25 application to the finished tie of a specially constructed band or layer.

One of the advantages achieved by the present invention lies in the fact that the strength and durability of the resultant article are unusually 30 good, and that the relatively delicate tie material is left intact and unimpaired, all stresses and strains being directed to, and taken up by, a special reinforcement strip or band.

In accordance with my present invention, the 35 tie includes a neckband portion which consists of inner and outer plies of material. These plies have their edges doubled inwards and stitched together, so as to form a relatively thick margin of at least four plies. The additional strip of material employed in the present construction is 40 purposely narrower than the neckband portion and lies in its entirety within the medial area between said margins. The added strip is stitched at its edges to the outside of the inner ply of tie 45 material; the stitches extend only through the inner ply; and the strip is selvaged along its longitudinal edges. By the term "selvage" as used herein and in the appended claims, I intend to refer to the type of selvage which is usually 50 provided by weaving during the manufacture of the fabric, whereby the resultant product is of single ply, substantially uniform thickness throughout.

The present added strip of material has a predetermined series of perforations which are ar-

ranged in longitudinally spaced relation, and a reinforcement band, arranged beneath the strip, has a similar set of perforations which register with the first-named set. Means marginally interengaging each pair of registering perforations 5 secures the reinforcement band permanently and efficiently in position. In the completed structure, the midportion of the neckband has no greater thickness than that of the margins; and the construction is characterized by an absolute 10 minimum of stitches which might impair the attractive appearance of the tie.

I achieve the foregoing objects, and such other objects as may hereinafter appear or be pointed out, in the manner illustratively exemplified in 15 the accompanying drawing, wherein—

Figure 1 is a perspective view of a tie of the ready-made variety, embodying the features of my present invention;

Figure 2 is an enlarged cross-sectional view 20 taken substantially along the line 2—2 of Figure 1;

Figure 3 is a perspective view of the added perforated strip of material shown in conjunction with the reinforcement band but dissociated from 25 the tie;

Figure 4 is a perspective view showing the manner in which the invention may be applied with equal facility to the type of tie that is not "ready-made"; and 30

Figure 5 is a perspective view showing the manner in which the invention is adapted to a four-in-hand type of tie.

The ready-made type of bow tie embodies the bow 10 and the preformed knot 11. Extending 35 in opposite directions from the rear of the knot 11 are the neckband portions 12 and 13. The neckband of the tie is adjustable in length by providing a hook 14 at the extremity of the portion 13 whereby this portion may be doubled back 40 upon itself to engage the hook in any one of a series of perforations provided in a predetermined arrangement. A metallic loop 15 is slidably mounted on the neckband portion 13 and is adapted to be engaged at its midportion by a hook 16 45 that is carried at the extremity of the neckband portion 12.

The manner of applying the hooks 14 and 16 to the extremities of the neckband portions has not been illustrated in detail, because these particular portions of the structure have no bearing 50 upon the present invention.

The present tie is made up of inner and outer plies 17 and 18, of relatively delicate and usually 55 ornamented tie fabric, and in the finished con-

struction the longitudinal edges of these plies are doubled inwards and stitched together, as at 19, whereby a relatively thick margin of at least four plies is provided. To those skilled in the art, it will be obvious that this mode of stitching requires that the plies 17 and 18 be initially stitched together in back-to-back relationship and thereafter turned inside out.

In accordance with my present invention, an additional strip of material 20 is stitched, as at 21, to the outside of the inner ply 17. The strip 20 is purposely narrower than the neckband by an extent which permits the stitches 21 to lie within the medial area between the thicker margins of the neckband. The strip 21 may be of any suitable material, preferably of a thin ornamental character, and its longitudinal edges 22 are selvaged so that when it is applied to the tie it constitutes only a single additional ply of material.

Along a medial longitudinal line, the strip 21 is provided with a series of longitudinally spaced perforations 23.

Associated with the strip 21 is a reinforcement band 24 which is of relatively staunch and tough material. This strip is also preferably selvaged along its longitudinal edges, and it is preferably somewhat narrower than the strip 21. Along a medial line it is provided with a series of openings or perforations 25 whose spacing corresponds to that of the perforations 23, whereby the two sets of perforations will register with each other when the band 24 is associated with the strip 21.

Each pair of registering perforations is marginally interengaged, and any suitable means may be employed for this purpose, although I prefer a series of buttonhole stitches 26. This marginal interengagement not only retains the perforations in permanent registry, but secures the reinforcement band 24 in position without the necessity for any adhesive or additional stitches.

In constructing the tie, the reinforcement band 24 is first applied to the strip 20, and after it is permanently secured in position the strip 20 is secured to the midportion of the ply 17 by means of the stitches 21. During this assembly, it will be observed that the reinforcement band 24 is disposed inwardly, so that it is thereby in completely concealed and sandwiched relation between the strip 20 and the ply 17. The ply 17 is then stitched, back to back, to the ply 18, and the tubular assembly is finally turned inside out.

Preferably, though not necessarily, the strip 20 carries markings 27, arranged adjacent to the perforations, respectively, to designate neckband sizes, so that when the length of the neckband is to be adjusted the hook 14 may be engaged with any selected perforation in accordance with the sizes enumerated on the strip 20.

The efficient nature of the complete assembly is shown most clearly in Figure 2, wherein it will be observed that the tie is no thicker at its midportion than at its margins. This arises from the fact that the strip 20 is selvaged at its edges and constitutes, therefore, a single ply throughout its width; also from the fact that the reinforcement band 24 is maintained in position without requiring any adhesive or additional objectionable stitching. It is further to be observed that the stitches 21 extend only through the inner ply 17 and the outside of the tie is, therefore, left completely smooth and unimpaired in appearance.

The compact and efficient nature of the structure results also from the fact that the strip 20 is sufficiently narrow to permit of its disposition

entirely within the medial area between the margins of the neckband. The relatively narrower width of the band 24 contributes also to this desirable result.

In Figure 4, I have shown the manner in which the invention is applied with equal facility to a tie that is not of the ready-made variety. In this case, the bow portions 28 and 29 are each provided with neckband portions 30 and 31, respectively. The portion 31 is permanently secured, as at 32, to a metallic elongated ring through which the other neckband portion 30 slidably extends. At the extremity of the portion 30 I provide a hook 33 corresponding to the hook 14 of Figure 1; and on the inside ply of the neckband portion 30 I attach the additional strip of material which is designated in Figure 4 by the reference numeral 34. This additional strip is applied as hereinbefore described in connection with Figures 1-3.

In Figure 5, the invention is shown applied to a ready-made four-in-hand type of tie. Detailed description of this figure is not believed to be necessary, since it will be obvious that the features hereinbefore described are exactly the same in Figure 5, except for the fact that the knot 35 is a four-in-hand type of knot instead of a bow knot.

It will also be understood that the invention is applicable to a regular four-in-hand tie, the tie in such a case being substantially identical with the tie illustrated in Figure 4, except that the ends 28 and 29 are considerably longer and are shaped in the conventional four-in-hand manner.

One of the advantages of the present invention lies in the ability to construct the strip 20 and the reinforcement band 24 in indeterminate and continuous lengths; or in providing the assembly shown in Figure 3 in such lengths. This can be accomplished at extremely small expense and independently of the tie assembly. Whenever it is necessary, in completing a given tie construction, to employ a portion of this strip material, a predetermined length may be cut off and attached to the tie, as hereinbefore described.

Even where the strip 20 is constructed in predetermined lengths, it is advantageous to be able to make the assembly of Figure 3 independently of the tie and merely to apply it, as required, to any selected tie that is being constructed.

It should be observed that the adjustments of the tie are made without in the least impairing the relatively delicate tie material. The hook 14, when engaged with a selected perforation, is entirely free of engagement with the ply 17, and any stress or strain is directed upon, and taken up by, the reinforcement band 24.

Also, because of the smooth exterior surface, the uniform thickness of the tie throughout its width, and the absence of unnecessary stitches, the entire device is unusually easy to use, simple to manufacture, and attractive in appearance.

It will be obvious that changes in the details, herein described and illustrated for the purpose of explaining the nature of my invention, may be made by those skilled in the art, without departing from the spirit and scope of the invention as expressed in the appended claims. It is, therefore, intended that these details be interpreted as illustrative, and not in a limiting sense.

Having thus described my invention, and illustrated its use, what I claim as new and desire to secure by Letters Patent is—

1. In an adjustable necktie, a neckband portion comprising inner and outer plies having their edges doubled inwards and stitched together to form a relatively thick margin of at least four plies, an additional strip of material, narrower than the neckband portion, stitched at its edges to the outside of said inner ply, said stitches extending only through the inner ply and lying within the medial area between said 5 margins, said strip having a series of perforations arranged in predetermined longitudinally spaced relation, said neckband portion being adapted to be doubled back upon itself and provided at its end with a hook adapted to engage 10 15 with a selected perforation, a reinforcement band underneath said strip and having perforations registering with those in said strip, and means marginally interengaging each pair of registering perforations for securing the reinforcement band in position. 20
2. In an adjustable necktie, a neckband por-
- tion comprising inner and outer plies having their edges doubled inwards and stitched together to form a relatively thick margin of at least four plies, an additional strip of material, narrower than the neckband portion, stitched 5 at its edges to the outside of said inner ply, said stitches extending only through the inner ply and lying within the medial area between said margins, said strip having a series of perforations arranged in predetermined longitudinally 10 spaced relation, said neckband portion being adapted to be doubled back upon itself and provided at its end with a hook adapted to engage with a selected perforation, a reinforcement band underneath said strip and having perforations 15 registering with those in said strip, and means marginally interengaging each pair of registering perforations for securing the reinforcement band in position, said reinforcement band being otherwise entirely free of connection with the necktie. 20

WILLIAM MAYER.
